UNITED STATES PATENT OFFICE.

JACOB J. UNBEHEND, OF SYRACUSE, NEW YORK, ASSIGNOR TO THE JUDSON L. THOMSON MANUFACTURING COMPANY, OF SAME PLACE.

CLASP-PLATE.

SPECIFICATION forming part of Letters Patent No. 416,695, dated December 3, 1889.

Application filed October 4, 1888. Serial No. 287,234. (No model.)

To all whom it may concern:

Be it known that I, JACOB J. UNBEHEND, of Syracuse, in the county of Onondaga, in the State of New York, have invented new and useful Improvements in Clasp-Plates, of which the following, taken in connection with the accompanying drawings, is a full, clear, and exact description.

My invention relates to improvements in the class of clasp-plates which are employed in connection with spring-clasp fasteners for use upon arctic overshoes and like devices; and it has for its object the production of a clasp or take-up plate which shall not only be simple to manufacture, but so constructed as to afford a rigid device not liable to bend or break, and at the same time to be light and easy-fitting upon the foot in use; and to this end my invention consists, essentially, of a clasp or take-up plate struck up out of sheet metal, having its side edges corrugated and crimped and provided with transverse slots.

It consists, furthermore, in making the take-up plate concavely curved crosswise thereof between the side bars of the plate, all as hereinafter more fully described, and pointed out in the claims.

In specifying my invention reference is had to the accompanying drawings, forming a part of this specification, in which like letters indicate corresponding parts in all the views.

Figure 1 is a top plan view of my improved clasp-plate, illustrating the preferred construction thereof. Fig. 2 is a like view of a modified construction slightly enlarged, the crimp of the metal being reversed from that shown in Fig. 1. Fig. 3 is a like view of a further modification, in which the side bars or edges of the take-up plate are slightly different in form from those shown in Fig. 2. Fig. 4 is an isometric view of my preferred construction, taken from an end of the plate and illustrating the contour transversely. Fig. 5 is a like view of the construction illustrated in Fig. 2, and Fig. 6 is a like view of the construction illustrated in Fig. 3.

A represents my improved clasp or take-up plate, struck up of thin sheet metal and having side bars a , transverse bars b , and transverse slot s . In the preferred example

of my invention, which is illustrated in Figs. 1 and 4, the take-up plate A is curved longitudinally to coincide with the contour of the instep of the human foot and the transverse bars b , which are concavely curved crosswise of the plate. The side edges a are corrugated and form the highest points of the concavely curved of the plate, and the edges a' are crimped under, serving to strengthen and stiffen the plate against bending when the device is in its operative position on the quarter of an arctic or like overshoe.

It will be observed that crimping the edges of the side bars a re-enforces the side edges a' , and at the same time affords a curved bearing for the plate to rest on when the device is applied to the foot of the wearer.

By reference to the drawings it will be seen that the curved bearing of the take-up plate is preferably the lowest point of the plate, or the point bearing upon the foot of the wearer, and as the same is rounded there is no liability of pinching or hurting the foot.

Heretofore much difficulty has been experienced in providing the requisite rigidity and stiffness in take-up plates of this character, since these plates are subjected to considerable strain by the movement of the foot in walking, and they were very liable to bend; or if the material was brittle they were very liable to become broken. My construction affords a plate of great rigidity and stiffness and insures great ease in wear by reason of the rounded surface bearing upon the foot. The peculiar bending of the transverse bars, so as to present a concave appearance crosswise of the plate, together with the crimped edges of the side bars a , imparts the requisite stiffness, and the aforesaid difficulties are entirely obviated and overcome thereby. Moreover, this construction permits the use of very light metal, which is much easier to manipulate in the dies employed in stamping out the device, and by forming the crimped edges a' of the side bars a to the contour of the foot a rounded surface is presented, which makes the plate rest easily on the foot of the wearer without any liability of pinching or hurting the foot.

As heretofore stated, Figs. 1 and 4 repre-

sent my preferred construction of the improved clasp-plate; but I do not restrict my invention to this specific form, since the plate may be made as shown in Figs. 2 and 5, or as 5 shown in Figs 3 and 6.

The construction illustrated in Fig. 2 is substantially the same, so far as concaving the device crosswise, as that illustrated in Fig. 1, but it differs in the crimping of the 10 side bars *a*.

It will be noted upon reference to Fig. 5 that the side bars *a* are bent down at 1, then bent angularly at 2, and the edge *a'* crimped down over the angular bend 2, thus elevating 15 the transverse bars somewhat above the plane of the bend 2. This construction is particularly applicable to the larger size of take-up plates and is exceedingly strong and durable.

The construction illustrated in Figs. 3 and 20 6 is substantially the same as that shown in Figs. 1 and 4, differing solely in the fact that the edges *a'* are crimped over the side bars *a* instead of underneath, as shown in the preferred example of my device. In this construction, however, the take-up plate rests 25 upon the reversely-curved plate instead of upon the edges thereof.

A special feature of advantage in concaving the transverse bars crosswise of the take-up plate rests in the fact that the spring-clasp tongue draws the plate down snugly to 30

the foot, thereby affording a better hold thereon than in the other forms of take-up plate heretofore employed.

Having thus fully described my invention, 35 what I claim as new, and desire to secure by Letters Patent, is—

1. In a fastening device, a clasp or take-up plate having its transverse bars concavely curved crosswise of the plate, substantially 40 as and for the purpose set forth.

2. In a fastening device, a clasp or take-up plate having its transverse bars concavely curved crosswise of the plate and its side bars crimped or bent back on themselves, substantially 45 as and for the purpose set forth.

3. In a fastening device, the herein-described take-up plate, having its transverse bars concavely curved crosswise of the plate and having the metal of its side bars bent in 50 a rounded curve, forming a rounded bearing for the plate, substantially as and for the purpose set forth.

In testimony whereof I have hereunto signed my name, in the presence of two attesting witnesses, at Syracuse, in the county of Onondaga, in the State of New York, this 24th day of September, 1888.

JACOB J. UNBEHEND.
